UNITED STATES PATENT OFFICE.

JOSEPH J. LOMBARDI, OF NEW YORK, N. Y.

ELECTRIC IGNITION DEVICE.

1,030,413.

Specification of Letters Patent. Patented June 25, 1912.

Application filed October 26, 1907. Serial No. 399,282.

To all whom it may concern:

Be it known that I, JOSEPH J. LOMBARDI, a citizen of the United States, and resident of the borough of Manhattan, in the city 5 and State of New York, have invented a new and useful Improvement in Electric Ignition Devices, of which the following is a specification.

My invention relates to an improvement 10 in electric ignition devices and has for its object to provide certain improvements in the construction, form and arrangement of the several parts of an electric ignition device whereby the liability of misfiring due to 15 the sparking points becoming covered with soot or the completion of the electric circuit from the electrode to the base of the device before reaching the sparking point is obviated.

20 A further object is to provide means for easily and minutely adjusting the relation of the sparking points so that the gap between them may be increased or diminished in the very slightest degree and locked in 25 such position without the necessity of bending or distorting the parts.

A practical embodiment of my invention is represented in the accompanying drawings in which—

30 Figure 1 is a longitudinal central section through the device, Fig. 2 is a side elevation of the same, and Fig. 3 is an inner end view of the device.

The conducting wire which forms one of 35 the electrodes is denoted by 1 and it is provided at its inner end with a sparking point 2 offset from the axis of the conducting wire. This conducting wire is preferably screw-threaded exteriorly for a portion of 40 its length for the purpose of securing the wire to the insulating block 3. This insulating block 3 surrounds the conducting wire 1 for a considerable portion of its length, which block comprises a reduced 45 tubular portion 4 and a cup-shaped enlarged portion 5. The means for securing the conducting wire 1 to the insulating block comprises a shoulder 6 which may be a nut screwed on to the wire in position to engage 50 the block within the cup-shaped portion, and a nut 7 arranged in position to engage the outer end of said insulating block. Washers 8, 9, may be interposed between the nuts 6, 7, and the insulating block.

55 The hollow base 10 embraces the cup-shaped end of the insulating block, said base

being provided with an interior annular shoulder 11 which is engaged by the inner end of the cup-shaped portion of the insulating block. Between the inner end of the insulating block and the interior annular shoulder 11 on the base, a washer 12 is inserted, which washer is composed of some suitable packing material, preferably mica.

A cap 13 embraces the reduced portion 60 of the insulating block and has a screw-threaded engagement with the outer end of the base 10. A washer 16 of some suitable packing material, preferably vegetable fiber, is interposed between the annular shoulder 70 15 formed by the reduction of the exterior dimension of the insulating block, and the inner end 14 of the cap 13. These washers 12 and 16 serve to prevent leakage between the insulating block and base and also allow 75 the insulating block to expand slightly under the influence of heat, thus preventing the block from cracking or breaking.

The base 10 has an enlarged outer portion 17 and also a reduced inner end portion 17*, 80 which portion 17* is intended to be brought into communication with the combustion chamber of an internal combustion engine. This reduced inner end portion 17* may be provided with an exterior screw-threaded 85 portion for permitting its engagement with the cylinder wall of the engine in connection with which the device is to be used. The end of this reduced end portion of the base is provided with a circular aperture 18 90 which is so situated as to be eccentric to the axis of the conducting wire 1 when the parts of the ignition device are in assembled adjustment. By making the aperture eccentric to the axis of the conducting wire, I provide an easy and exact method of regulating 95 the distance between the sparking point of the conducting wire and the wall of the aperture 18. This regulation or adjustment is accomplished by loosening the lock nut 7 100 and turning the conducting wire 1 until the sparking point of the wire is brought to the exact distance desired from the wall of the aperture 18, which forms the other sparking point, the said sparking point on the wire 105 being offset in the present instance by bending the same at an angle to the conducting wire so that as the conducting wire is turned, the sparking point will be brought toward and away from the wall of the aperture. 110 After the parts have been adjusted with the greatest accuracy to the point which will

produce the best results, the lock nut 7 may be tightened so as to secure the parts in said adjustment. This adjustment of the spark gap is an important feature of my invention 5 for the reason that the slightest variation in the distance between the sparking points affects the value of the spark.

The walls of the recess 19 in the reduced portion 17* of the base form a continuation 10 of the walls of the recess 5* in the cup-shaped inner portion of the insulating block 3 so as to form a sparking chamber around the conducting wire 1. Also by projecting the inner portion of the conducting wire 15 centrally through the recesses in the cup-shaped portion of the block and the reduced end of the base 10, the said conducting wire is spaced a considerable distance from the walls of the base and the wall of the insulating block, thus obviating possibility of 20 short-circuiting by the continuous deposit of carbon which will bridge the space from the conducting wire to the base. This arrangement also prevents any tendency on the part 25 of the current to jump between the wire and the base at any other place than at its sparking points. This construction also tends to prevent the accumulation of carbon deposit and oil in the recess 5* of the insulating block.

An ignition device constructed in accordance with my invention will be extremely strong and durable and can be used for a long time without cleaning, the inclosed 35 chamber surrounding the inner end of the conducting wire serving to produce a self-cleaning effect which will keep the sparking point on the conducting wire and the walls of the aperture clean and thus at their highest efficiency.

What I claim is:

1. An electric ignition device comprising a hollow base portion, an insulating block fitted therein, a conducting wire rotatably mounted in the insulating block, the said 45 base portion being provided with a true circular opening in its inner end eccentric to the axis of the said conducting wire, and a sparking point secured to the inner end of the said conducting wire and projecting at 50 an angle to the axis of the latter.

2. An electric ignition device comprising a hollow base portion, a hollow insulating block fitted therein and provided with a cup-shaped portion, a cap for holding the block 55 in the base, a conducting wire of relatively small diameter rotatably mounted in said block, and a sparking point fixed in the inner end of the conducting wire and projecting at an angle to the axis thereof, said base 60 portion being provided in its inner end with a true circular opening eccentric to the axis of the said wire, whereby the rotation of the said wire will cause the said point to approach or recede from the walls of said opening at an even rate while the conducting wire proper remains the same axial distance from the walls of the said openings, and the said recesses in the block and base being so arranged as to form a continuous hollow 70 chamber of uniform diameter about the conducting wire proper.

In testimony, that I claim the foregoing as my invention, I have signed my name in presence of two witnesses, this twenty-third 75 day of October 1907.

JOSEPH J. LOMBARDI.
